UNITED STATES PATENT OFFICE.

EMORY E. ELLIS, OF ORANGE, MASSACHUSETTS, ASSIGNOR TO UNION CALIPER COMPANY, OF ORANGE, MASSACHUSETTS.

DESIGN FOR A TOOL-HANDLE.

47,416.

Specification for Design.

Patented June 8, 1915.

Application filed February 2, 1914. Serial No. 816,108. Term of patent 7 years.

To all whom it may concern:

Be it known that I, EMORY E. ELLIS, a citizen of the United States, residing at Orange, in the county of Franklin, Commonwealth of Massachusetts, have invented a new, original, and ornamental Design for Tool-Handles, of which the following is a specification, reference being had to the accompanying drawing, forming a part thereof.

Figure 1 is a side elevation of a tool handle, showing my new design, and Figs. 2, 3 and 4 are vertical sections taken respectively on the lines 2—2, 3—3, and 4—4 of Fig. 1.

The essential feature of my invention resides in the concaving of the shank of the handle on two sides as indicated at *a*. These

concavities are preferably of such depth as to be tangential to the two horizontal radii of an inscribed circle having the center of the shank as its approximate center. The concavities give to the handle an ornamental and attractive appearance not present where the shank of the handle is of the conventional cylindric shape while adding practically nothing to the cost of producing and finishing the handle.

I claim:

The ornamental design for a tool handle, as shown and described.

EMORY E. ELLIS.
